UNITED STATES PATENT OFFICE.

**ZOTIQUE BEAUDRY, OF LYNN, MASSACHUSETTS, ASSIGNOR TO UNITED-XPEDITE
FINISHING COMPANY, OF BERWICK, MAINE, A CORPORATION OF MAINE,
TOOL FOR FINISHING THE HEELS OF BOOTS AND SHOES.**

Specification of Letters Patent, Patented Apr. 30, 1912.
Application filed March 8, 1906, Serial No. 304,380.

To all whom it may concern:

Be it known that I, ZOTIQUE BEAUDRY, a citizen of the United States, residing at Lynn, in the county of Essex and State of Massachusetts, have invented new and useful Improvements in Tools for Finishing the Heels of Boots and Shoes, of which the following is a specification.

10 This invention relates to a tool for finishing the heels of boots and shoes—that is, for polishing the edge of the heel and imprinting a row of indentations around that portion of the heel which is adjacent to the upper. In other devices of this character
15 now in use a guide lip or flange is employed in conjunction with a polishing wheel and a disk having a milled peripheral acting face, and herein called the "milling" disk or tool, for forming the row of indentations.
20 The guide enters the depression or "rand crease" between the top of the heel and the adjacent face of the upper for positioning the heel laterally with relation to the milling disk. It is often the case that the rand
25 crease varies in depth or that it is deeper in one shoe than in another. If the guide were to be made large enough in diameter so that it would bottom in or reach to the bottom of a deep rand crease while the
30 milling disk were in contact with the heel, it would be so large as to prevent the milling disk from coming into contact with the heel and making the row of distinct indentations which is desirable when the crease
35 was shallow. If, on the other hand, the guide were to be made the right diameter relatively to the milling disk to bottom in the shallow rand crease while the milling disk were in contact with the heel, it would
40 be so small as to fail to bottom in a deep rand crease. If the guide fails to bottom in the rand crease it is free to engage either side of the crease, that is, to contact with and guide the shoe either by the lower wall
45 of the crease which is formed by the top end of the heel or by the upper wall of the crease that is formed by the shoe upper at the heel seat. The guide in such a case therefore fails to position the shoe uniformly in lateral relation to the milling disk
50 and as a consequence the row of indentations formed by the disk is not always at the desired uniform distance from the upper end

of the heel and is liable to be crooked or wavy. As the row of indentations is always located close to the edge of the heel a slight variation from the desired uniform distance or any wavering or divergence from the desired formation is readily noticeable and detracts from the appearance of the finished shoe.

One object of this invention is to provide in combination with a milling disk a movably mounted guide which shall at all times bottom in the rand crease, whether said crease be shallow or deep. By this arrangement the guide always engages both walls of the crease and, therefore, positions the heel definitely with relation to the milling disk so that the line of indentations formed by the disk may be made at a uniform distance from the top edge of the heel and may be of a uniform depth in all parts of the heel unaffected by variations in the depth of the rand crease. In the construction shown the rand guide is yieldingly mounted by means permitting it to move radially with relation to the milling disk in different directions according to the position in which the heel is presented against the disk. 65 70 75 80

Another object of the invention is to provide in combination with a milling disk arranged to form a line of indentations at a distance from the top of a heel, heel polishing means constructed and arranged to be driven for rubbing the surface of the heel on both sides of the line of indentations, and a rand guide that is movably supported with relation to the milling disk and polishing means. By the use of such a finishing tool a heel may be properly milled and polished on both sides of the line of indentations at the same time. A novel construction and arrangement of the polishing means and the milling disk is also preferably employed, comprising a polishing wheel made in two connected parts, the milling disk being mounted between the two parts and arranged to turn independently. As shown the two parts of the polishing wheel are connected by an intervening reduced section upon which the milling disk is arranged to turn freely. Preferably one or both of the two parts of the polishing wheel is chambered to form a reduced section of considerable width and a milling

disk is provided with a laterally extending hub fitting said reduced section. This arrangement provides a firm support for the milling disk which insures its running steadily.

5 The several features of the invention, including certain details of construction and combinations of parts, will be explained in the following description and pointed out 10 in the claims.

10 Referring to the drawings: Figure 1 is a side elevation of my improved finishing tool for boots and shoes. Fig. 2 is a section on line 2—2 of Fig. 1, partly broken away 15 to save space in the drawings. Fig. 3 is a section similar to Fig. 2, partly broken away to save space in the drawings. Fig. 4 is a diagram illustrating the relation of my polishing wheel and guide to a heel, in 20 which the guide is shown eccentric to the polishing wheel. Fig. 5 is a diagram illustrating the relation of my improved polishing wheel and guide to a heel, in which the guide is shown concentric with the polishing 25 wheel.

Like numerals refer to like parts throughout the several views of the drawings.

In the drawings, 10 is a polishing wheel adapted to polish the heels of boots and 30 shoes after the preliminary trimming and burnishing operations have taken place. The polishing wheel 10 is mounted upon a shaft 11, which may be rotatably mounted in suitable bearings (not shown) and driven 35 by a pulley and belt (not shown). The shaft 11 is provided with a bore 12 extending longitudinally thereof, said bore terminating in a shoulder 13 at the right hand end thereof. The shaft 11 is also provided 40 with a bore 14 extending longitudinally thereof, said bore being smaller in diameter than the bore 12. A rod 15 is mounted within the shaft 11 and comprises a cylindrical portion 16 which closely fits the recess 45 14 of the shaft 11. The rod 15 also comprises a tapered extension 17 which is of smaller diameter than the recess 12 and is adapted to yield laterally therein. The tapered extension 17 terminates in a 50 shoulder 18 which bears against the shoulder 13 and is drawn firmly in contact therewith by means of a nut 19 having screw-threaded engagement with the cylindrical portion 16 of the rod 15, said nut acting to clamp the 55 rod 15 rigidly to the shaft 11 and cause it to rotate therewith.

The polishing wheel 10 is formed in two parts, a main portion 20 and a cap 21 fast thereto by means of screws 22. The main 60 portion 20 of the polishing wheel 10 is provided with a recess 23 and a reduced section 24 extending therefrom. A milling disk 25 is rotatably mounted upon the reduced section 24 and has a laterally ex- 65 tended hub partly within the recess 23, the

cap having a corresponding recess which receives the hub and a portion of the reduced section 24. The cap 21 closely confines the milling disk 25 and holds the same against endwise movement with relation to the polishing wheel 10 while permitting it to turn on the hub independently of the polishing wheel. Said disk 25 is provided on its periphery with a continuous series of serrations 26 adapted to mill a heel or imprint upon the heel the line or row of indentations. The milling disk is arranged to form the line of indentations around the upper portion of the heel at a short distance from its top end, as shown in Figs. 2 and 3. 75

A rand guide having a lip 27 to enter the rand crease 31 between the upper and the top of the heel is mounted upon the outer end of the rod 15 which is free or unconfin'd so that the guide can move radially 80 with relation to the milling disk in any direction according to the direction of the pressure of the heel against it. The guide is located adjacent to the cap 21 of the polishing wheel 10, and is provided with a recess 28 which permits its lateral movement 85 with relation to the milling disk 25 and also the polishing wheel 10. The guide 27 is also provided with a polishing face 29 adapted to polish or bead the top face of 90 the heel which forms the lower wall of the rand crease, the other wall of which crease is formed by the adjacent portion of the upper, it being understood that the word "heel" is used in a general sense and includes that portion of the sole of the shoe which intervenes between the heel proper and the upper. The rod 15 acts to hold the rand guide 27 normally concentric with the polishing wheel 10, but the tapered extension 17 thereof is adapted to yield and permit the guide to move in a direction substantially at right angles to the axis of the shaft 11 or radially with relation to the 95 milling disk. 100

In the use of the finishing tool the operator presents the shoe in position for the rand guide to enter the rand crease, pressing the heel against the tool until the rand guide bottoms in or reaches the bottom of 115 the rand crease where it contacts with both the upper and lower walls of the crease and firmly positions the shoe laterally with relation to the milling disk. The pressure is continued, the rand guide yielding, until the heel is forced firmly against the milling disk, the teeth or serrations of which enter the edge of the heel and form indentations in its surface. The shoe is then turned, causing the milling disk, which is free to 125 rotate in rolling contact with the heel, to make a row or line of indentations along the edge of the heel. In this movement of the shoe the heel is guided with relation to the milling disk by the rand guide with 130

which the shoe is always maintained in the same lateral relation because the guide bottoms in the rand crease and guides the shoe by contact with both walls of the crease. 5 The line of indentations is, therefore, formed at a uniform distance from the top of the heel all the way around, being as accurately located opposite a deep wide portion of the crease as it is beside a narrow 10 shallow portion. Also the indentations may be of the same depth at all parts of the heel, notwithstanding variations in the depth of the rand crease, because the yieldingly supported guide permits the heel to be held in 15 constant uniform contact with the milling disk all the way around the heel edge. The relation of the guide and the milling disk to the work as the rand crease varies in depth is illustrated in Figs. 2 and 3. 20 Referring to Figs. 4 and 5 in which the periphery of the guide 27 and the periphery of the polishing wheel 10 are indicated by circles, it will be seen that the rand crease 31 varies in depth from *a* to *b* (Fig. 4) and 25 that a pressure sufficient to cause a yielding of the rod 15 will result in the periphery of the guide remaining in contact with the bottom of the crease and also in the periphery of the milling disk remaining in contact 30 with the heel throughout the entire operation, whereas in Fig. 5 the rand crease 31 is constant in depth from *a* to *b* and is of maximum depth, in which case the rod 15 will not yield, but the rand guide will 35 remain in contact with the bottom of the rand crease from *a* to *b*, and the milling disk will remain in uniform contact with the heel 30 throughout the operation. It will thus be seen that the guide which is made large 40 enough in diameter to bottom in rand creases of maximum depth, is adapted to yield and accommodate itself to creases of minimum depth without disturbing the relation of the milling disk 25 and the polishing wheel to 45 the heel. Consequently the guide, the periphery of which is always in contact with the bottom of the rand crease 31, cannot move from side to side in the depression. It will be evident that this construction 50 provides for the accurate and certain guiding of the heel with relation to the finishing tool.

While the invention is herein shown as embodied in a heel finishing tool comprising 55 a polishing wheel as well as a milling disk and a relatively yielding rand guide, it is evident that the disk 25 hereinbefore described may be omitted and the yielding guide used in connection with the polishing 60 wheel, or if it is simply desired to bead the heel of the shoe without polishing said heel the polishing wheel may be omitted and the milling disk used in combination with the rand guide arranged as described without 65 departing from the spirit of my invention.

Having thus described my invention, what I claim and desire by Letters Patent to secure is:—

1. In a heel finishing machine, the combination with a milling disk having a serrated periphery for making a line of indentations around the edge of a heel, of means for guiding said milling disk laterally with relation to the heel seat end of the heel, comprising a guide formed to enter the rand crease, and means for supporting the crease guide to permit yielding movement thereof radially in all directions with respect to the milling disk for bottoming in creases of different depths. 70

2. In a heel finishing machine, the combination with a milling disk having a serrated periphery, of a rand crease guide having a laterally fixed relation to the milling disk, and means for supporting the guide to permit yielding movement thereof radially in all directions with respect to the disk for bottoming in creases of different depths. 80

3. In a heel finishing machine, the combination with a milling disk having a serrated periphery, of a rand crease guide, and means for supporting said milling disk and rand crease guide in predetermined lateral relation, said means having provision for relative free yielding movement of the milling disk and crease guide radially of the disk in a plurality of directions to allow the guide to bottom in rand creases of different depths. 90

4. A finishing tool for boots and shoes 100 comprising in its construction a milling disk, a rotary polishing wheel rotatably mounted in working relation thereto, and a rand guide freely movable radially in several directions relatively to the periphery of 105 said disk.

5. A finishing tool for boots and shoes comprising in its construction a rotary hollow shaft, a polishing wheel mounted thereon, a serrated milling disk rotatably mounted in 110 working relation with said wheel, a spring mounted within said shaft, and a rand crease guide carried by said spring, said spring being adapted to permit the guide to yield radially in a number of directions 115 relatively to said milling disk.

6. In a finishing tool for boots and shoes, a rotary polishing wheel formed in two parts, a milling disk journaled to rotate thereon and between said two parts, a hollow shaft upon which said polishing wheel is mounted, a rand guide, and a rod extending longitudinally within said shaft, one end of said rod being fast to said shaft and the other end of said rod being fast to said 120 guide. 125

7. In a machine for finishing the heels of boots and shoes, a rotary work rubbing wheel comprising two parts arranged to be actuated together and having an interven- 130

ing reduced portion or hub formed between them, a milling disk disposed between said two parts and freely rotatable on said hub, and a crease guide independent of said disk and wheel.

8. In a heel finishing machine, the combination with a milling disk for making a line of indentations around the edge of a heel, of a rand crease guide, and means for supporting the crease guide to permit it to yield radially with relation to the milling disk in different directions as a heel is pressed against it in different positions.

9. In a heel finishing machine, the combination with a milling disk for making a line of indentations around the edge of a heel, of a rand crease guide, and means for supporting the crease guide and the milling disk for relative yielding movement radially in different directions as the work is pressed against them to permit the disk to indent to the same depth portions of the heel in which the rand crease varies in depth.

10. In a heel finishing machine a hollow shaft, a heel rubbing tool secured rigidly

on said shaft, said tool comprising two sections secured together for simultaneous movement, one of said sections having a reduced or hub portion formed thereon, a milling disk interposed between said sections and having an extended hub mounted on said reduced portion for rotative movement thereon, said disk having teeth projecting slightly beyond the work engaging surfaces of said sections, a second shaft supported concentrically within said hollow shaft and a rotary rand crease guide supported thereon close to the end of said tool, said second shaft for a considerable distance being of less diameter than the bore of said hollow shaft whereby the guide may yield relative to the milling disk and tool.

In testimony whereof I have hereunto set my hand in presence of two subscribing witnesses.

ZOTIQUE BEAUDRY.
